OVERLAPPING LINKAGE ENGAGEMENT FOR
MODEL-FORMING SHAPED SHEET PIECESWilliam J. Wiswesser, near Stony Creek Mills,
Pa., assignor to Willson Products, Inc., Reading,
Pa., a corporation of Pennsylvania

Application September 5, 1946, Serial No. 694,913

4 Claims. (Cl. 35—18)

1

My invention relates to assembled figure structures formed by linking together separate shaped pieces of thin resilient sheet material; and more particularly it consists of a new and improved means for detachably joining the shaped pieces by an overlapping, self-locking, flexible, linkage engagement of their marginal edges.

One important use of such linkage engagement, is the production of improved atomic and molecular models of simplified and realistic representations for visual demonstrations in class room teaching, and as an aid in building complex repeating structures for polymer research studies.

Other important uses may be found in occupational therapy treatments, as interesting means for developing mental and muscular facilities; as a constructive educational toy for children; and as a means for producing novelty combinations for ornamental and decorative displays.

More specifically my invention comprises forming each of two sheet pieces to be united, with a locking aperture adjacent the marginal edge of each, and by simple overlapping movement of said pieces, engaging the marginal edge of each in the locking aperture of the other sheet, one at least of said sheet apertures having an entrance slit thereto from its marginal edge, yielding to admit entrance of the marginal edge of the other sheet into its locking aperture.

The nature of my invention and the manner of its operation will be more fully described herein-after in connection with the accompanying drawings, and the novel features thereof set forth in the appended claims.

In the drawings:

Fig. 1 is a plan view of one model-forming piece embodying my invention, and shown in the preferred shape of a disc.

Fig. 2 is a cross sectional view thereof, taken on the line 2—2 of Fig. 1.

Fig. 3 shows two overlapping disc pieces in incompletely engaging relation to one another.

Fig. 4 shows the completed linked engagement of three disc pieces.

Fig. 5 shows a possible linkage engagement of a plurality of disc pieces.

Figs. 6, 7, 8 and 9 show modified variations of the shape of the sheet pieces, and of the locking apertures therein.

Fig. 10 shows my locking apertures applied to a disc having a known slotted aperture for right-angled engagement with a like slotted disc.

Fig. 11 is a perspective view of two of the Fig. 10 slotted discs in right angled engagement.

The disc piece 5 shown in Figs. 1 and 2, is

formed of any suitable thin flexible material, transparent plastic material in this preferred disc shape being desirable and particularly effective in building up atomic and molecular models.

5 The linkage connection for an added disc, as shown, consists of a round aperture 6 set inward from the peripheral edge 7 of the disc. This aperture 6 has an opening thereto formed by a slit 8 extending thereto from said peripheral edge 7. 10 And as an essential of my invention, the diameter 9 of aperture 6 (Fig. 2) is necessarily greater than the length 10 of slit 8 (Fig. 2) for a purpose hereinafter described; and the marginal sections 11 and 12 on each side of slit 8 are normally in substantial contact, but may temporarily yielding flex in opposed directions to provide an open passage way to aperture 6.

The disc 5 thus formed with its locking aperture 6 and entrance slit 8 thereto, as described, 20 is adapted, without the use of any tool or added bonding connection, to join and interlockingly engage with another piece or disc provided with a like aperture of greater diameter than its spaced location inward from its marginal edge.

25 In Fig. 3 I have indicated disc 5 with its aperture 6 and entrance slit 8 in an incompletely engagement with a similar disc 5a, having in this case a closed aperture 6a. Their interlocking engagement may be simply effected, using the 30 closed marginal section 13 of disc 5a to flex marginal sections 11 and 12 out of the plane of their disc 5, and in opposite directions, to provide an open passageway for overlapping movement of the marginal edge 13 of disc 5a into aperture 6 of disc 5. The marginal edges 11 and 12 of disc

5 at the same time move into aperture 6a of disc 5a and, due to the resilient nature of the material, resume their parallel substantially contacting relation to securely lock the two discs in linked 40 engagement, but detachable by reversal of the described engaging movements.

The interengagement of the discs 5 and 5a may be best effected when they are in substantially flat parallel relation to one another, but I do not 45 wish to limit myself to such disposition, as they may be linked while standing in any angular relation up to relatively right-angled positions.

In Fig. 4 I have indicated the complete linked engagement of two discs 15 and 16 by an interposed connecting disc 17, and it will be noted that disc 17 stands in a plane at right angles to the planes of discs 15 and 16. This right-angled relation of a disc thus locking engaged with another, is normal, but quite flexible, and may be held fixed or provided with increased flexibility

depending upon the shape and location of the locking apertures as later herein described.

Each disc used must have at least one locking aperture, and may have a plurality when desired, and, particularly for atomic and molecular models, these apertures may be geometrically disposed according to the ideal or equilibrium positions of linkage. And it is of course obvious that the aperture of one of two discs to be linked together must have an entrance slit thereto; and it is also obvious, for economy of manufacture, that all apertures may be provided with an entrance slit if desired, without fundamental change in the above described manner of their linking engagement.

In Fig. 5 I have indicated discs thus formed with multiple locking apertures each provided with an entrance slit, and have shown a number of discs linked together to indicate a possible composite figure formation.

While disc shape of the pieces best lends itself to the needs of many figure assemblies and models, their shape may be varied as desired or required.

For instance in Fig. 6 I have indicated a half-disc shape 20, in Fig. 7 a triangular shaped piece 21, in Fig. 8 a rectangular shaped piece 22 and in Fig. 9, a modified triangular shaped piece 23. And in Fig. 7 I have indicated the locking apertures 25, 25, 25 as of oval shape, and due to the location of their entrance slits, as shown, the lateral margins of said apertures are reduced, providing increased flexible movement of an interlinked piece. In Fig. 8 I have shown the apertures 26, 26, as rectangular with their width closely approximating the thickness of an attached piece, reducing to a practically fixed relation the position of such interlinked pieces.

In Figs. 10 and 11 I have indicated my invention applied to a known radially slotted piece 30 adapted to receive and secure at right angles a similarly slotted companion piece 31, such arrangement providing for a ball-like structure by interlinked added pieces.

As previously stated the diameter, or depth, of the locking apertures in each disc, or shaped piece, must be greater than its spacing from its marginal edge, and this is obviously essential in order that the marginal sections outside said apertures will be narrow and readily engage within the diameter or depth of their connected disc or shaped piece apertures.

From the foregoing description it will be readily seen that I provide a simple and effective self-contained linkage interengagement of separate pieces into a composite figure shape or model. That such linkage engagement is variably flexible; that only a small amount of energy is required to spring open the marginal sections 11 and 12 on each side of entrance slit, and when sprung together securely lock said links together in a strong interengagement. And when such disc or shaped pieces are used in making atomic or molecular models, the energy required to interengage them realistically represents a corresponding chemical activating energy.

What I claim is:

1. Separate model forming pieces of thin resilient sheet material linkably engageable with companion pieces into a composite figure structure, each piece consisting of a sheet of determined outline and having at least one linkage aperture occupying a small portion of the total area of the

piece and spaced inwardly from its marginal edge and adapted to engage with the marginal section enclosing a like aperture in a companion sheet, the apertures in said discs being spaced inwardly from their marginal edges at like distances, and having an inwardly extending depth length greater than the width of its inward spacing from said margin, and the aperture of one sheet having an entrance slit thereto from said marginal edge in alignment with the axial depth length of its aperture.

2. Separate model-forming disc-shaped pieces of thin resilient material overlappingly linkable at substantially right angles with similar disc pieces to form a composite unit, each disc piece having a circular aperture occupying a small portion of the total area of the piece and spaced inwardly from its marginal edge and adapted to linkingly engage with the marginal section encircling the aperture of a companion disc piece, each aperture having a slightly greater diameter than its spaced distance from its marginal edge so that joined pieces will assume an angular relationship, the aperture of one of said disc pieces having an entrance slit thereto from the marginal edge of its disc.

3. In combination, a disc-shaped piece of thin resilient material overlappingly linked at substantially right angles with a similar disc piece to form a composite unit, each disc piece having an aperture occupying a small portion of the total area of the piece and spaced inwardly from its marginal edge and adapted to linkingly engage with the marginal section encircling the aperture of the companion disc piece, the aperture of one of said disc pieces having an entrance slit thereto from the marginal edge of its disc, the disc sections on each side of said entrance slit normally lying in substantially contacting relation in the plane of said disc and flexibly bendable out of said plane to form an entrance passage-way to said aperture, the slits of said joined pieces being disposed so as to be substantially in alignment.

4. In combination, a disc-shaped piece of thin resilient material overlappingly linked at substantially right angles with a similar disc piece to form a composite molecular model unit, each disc piece having a circular aperture occupying a small portion of the total area of the piece and inwardly spaced from its marginal edge and of slightly greater diameter than its inwardly spaced distance from said edge and thus adapted to linkably engage at right angles with the marginal section enclosing the aperture of a disc piece to be linked therewith, and the aperture of both of said disc pieces having an entrance slit thereto from its marginal edge, the slits of said joined pieces being disposed so as to be substantially continuous and in alignment.

WILLIAM J. WISWESSER.
